ELECTRIC SWITCH

Stephen S. Grady, New York, N.Y.

Application September 13, 1945, Serial No. 616,073

15 Claims. (Cl. 200—16)

1

This invention relates to electric switches in general and more especially to two-way switches, either for alternately connecting a common generator to one or another of two power lines, or for alternately connecting a single power line to one or another of two generators.

Among the objects of the present invention, it is aimed to provide an improved two-way electric switch having a common fuse when the switch is in either of its two closed positions and a slideable interposer actuatable either into neutral position or into either of the two closed positions of the switch.

It is still another object of the present invention to provide an improved electric switch having a pivoted handle for actuating an interposer into and out of closed position and a switch box having a cover cooperating with the handle so that the box or cover of the box cannot be opened without first actuating the switch handle into neutral or open position, and in turn whereby the opening of the cover will force the handle into neutral or open position if it is not already in neutral position.

It is still another object of the present invention to provide an improved electric switch having a pivoted handle for actuating an interposer into and out of one of two closed positions and a switch box having a cover cooperating with the handle so that the box or cover of the box cannot be opened without first actuating the switch handle into neutral or open position, and in turn whereby the opening of the cover will force the handle into neutral or open position whether the handle is in one or the other of its closed positions, if the handle is not already in neutral position.

It is still another object of the present invention to provide an improved electric switch having a pivoted handle for actuating an interposer into and out of closed position, and a switch box having a cover and anchoring means locking said handle in neutral position when said cover is being removed or is removed and the cover will cooperate with said anchoring means to free said handle when said cover is actuated into closed position.

It is still another object of the present invention to provide an improved electric switch having a pivoted handle for actuating an interposer into and out of closed position and a switch box having a cover, said handle consisting of two pieces pivoted to one another to enable folding one piece into compact arrangement with the switch unit when the cover is removed

2

to conserve space when shipping the switch and also to afford access to a centrally located fuse.

It is still another object of the present invention to provide an improved electric switch having a plurality of parallel fuses with blade ends to cooperate with flexible clamping jaws, and a bar constituting a fuse puller in anchored position securing the several fuses from being accidentally jarred loose, said bar having a pin formed to enter any one of the jaws when the bar is freed to cooperate with a blade end and remove a fuse.

These and other features, capabilities and advantages of the present invention will appear from the subjoined detail description of one specific embodiment thereof illustrated in the accompanying drawings in which

Fig. 1 is a side elevation partly in section of a switch box and electric switch made according to the present invention;

Fig. 2 is a plan view of the electric switch slightly enlarged as to the scale of Fig. 1;

Fig. 3 is a section on the line 3—3 of Fig. 2;

Fig. 4 is a section on the line 4—4 of Fig. 2; Figs. 5, 6, 7 and 8 are fragmental side elevations of the electric switch illustrating four different circuit connections that may be made with an electric switch made according to the present invention;

Fig. 9 is a section on the line 9—9 of Fig. 2.

In electric switch boxes, it is not unusual to actuate electric switches of two, three and even four associated conductors, as for instance a two-wire direct current circuit, a three-wire hookup for a three-phase alternating current hookup or a four-wire hookup for a four-phase alternating current hookup. The features of the present invention are adapted to any one of these hookups, and merely by way of example, in Fig. 2, there is illustrated an electric switch construction adapted for three electric switches of three associated conductors, to wit the electric switches 1, 2 and 3.

Since each of the electric switches 1, 2 and 3 is substantially identical with one another, only one switch, to wit the switch 2 will be described in detail, and the like parts in electric switches 1 and 3 will have the same reference characters applied.

As shown in Figs. 2 and 4, there is provided a base 4 composed of some suitable insulating material common to all three switches 1, 2 and 3, and it is provided with projections 5, 5 secured to the base wall 6 of the switch box 7 which in turn is provided with end walls 8 and 9, the wall

8 having pivotally connected thereto, by the hinge 10, the cover 11, which is provided with an overlapping or extended portion 12 having an opening to receive the hasp 13 riveted to the flange 14 of the wall 9. When the cover 11 is in closed position shown in Fig. 1, where the hasp 13 extends through the extension 12, a conventional padlock 15 may be secured to the hasp 13 to lock the cover 11 in closed position.

When three switches, as an instance, the switches 1, 2 and 3, are associated, they are spaced from one another by the longitudinally extending bars 16 and 17 composed of insulating material, with the bar 16 between the switches 1 and 2 and the bar 17 between the switches 2 and 3.

Extending transversely across the bars 16 and 17, there are provided the two plates 18 and 19 composed of insulating material, separated from one another and mounted on blocks or enlargements 20 composed of insulating material extending from the bars 16 and 17. Mounted on the transverse plates 18 and 19, there are provided the cheek plates 21 and 22 composed of insulating material and in alinement with the bars 16 and 17 respectively to form stalls or working spaces for the switches 1, 2 and 3.

With particular reference to Figs. 2 and 4, each of the switches 1, 2 and 3 is provided with a main contact plate 23 secured to the base plate 4 and provided with a terminal 24. This contact plate 23 extends from one end of the base plate 4 approximately two-thirds the length of the base plate 4 and has a raised portion 25 with two cam faces 26 and 27 at the ends of the raised portion 25. This raised portion is disposed in the present instance about midway between the transverse plates 18 and 19. The transverse plates 18 and 19 have mounted on the same the U-shaped contact plates 28 and 29. The legs 30 and 31 of the contact plates 28 and 29 respectively are substantially in alinement with one another and spaced from the transverse plates 19 and 18. The leg 30 is also spaced from the contact plate 23 and the leg 31 in the present instance spaced from the base plate 4.

In the present instance, extending adjacent the faces of the cross bars 19 and 18, facing the legs 30 and 31 respectively, there are provided the contact plates 32 and 33 having the flexible portions 34 and 35 respectively which plates 32 and 33 are secured to the plates 36 and 37 respectively secured to the faces of the bars 19 and 18 extending away from the legs 30 and 31. Between the plates 36, 37 and the bars 19, 18, preferably there are secured the webs 38 and 39 of the fuse clamping jaws 40 and 41 respectively.

The plates 36 and 37 have the flexible contact portions 42 and 43 respectively extending toward one another in the space between the plates 32 and 33, the plates 36 and 37 having inclined shoulders 44 and 45 respectively for the purposes hereinafter to be described.

The U-shaped contact plate 28 is insulated from the edges of the plates 32 and 36 by the sheet 46 composed of some suitable insulating material and preferably extending up inside of the U-shaped plate 28 around the free edge of the plate 32, one portion of the bar 19 and then upwardly between the opposing edges of the plate 28 and plate 36. Similarly, the U-shaped plate 29 is insulated from the plate 33 and the plate 37 by the sheet 47 composed of a suitable insulating material which is disposed on the inside of the plate 35 and between the upper edge of the plate 35 and the plate 29 and then up over a portion

of the bar 18 to extend between the opposing edges of the plate 29 and the plate 31.

Mounted to slide on the bars 16 and 17 is the plate 48 composed of insulating material and having around its edges the U-shaped contact plates 49 and 50.

The plate 48 in the present instance is common to the three switches 1, 2 and 3 but each of the switches has an individual pair of contact plates 49 and 50.

For operating the plate 48 and its three sets of contact elements 49 and 50 commonly known as an interposer, there are provided the two arms 51 and 52. The bars 51 and 52 are pivotally connected by the pins 53 and 54 to the upper ends of the cheek plates 21 and 22 and the lower ends of the bars 51 and 52 are enlarged, see Fig. 4, and have three fingers, 55, 56 and 57 cooperating in three openings formed in the plate 48. The arms 51 and 52 are operatively connected to two springs 58 and 59. These springs are substantially identical to one another and cooperate with the arms 51 and 52 to anchor the arms in neutral position against accidental displacement and also to anchor the arms in either of its two circuit closing positions and still furthermore cooperate with the arms to effect a quick opening and quick closing in order to reduce arcing to a minimum.

The spring 58 as an instance has one arm 60 disposed against the screw 61 constituting an abutment secured to the cheek plate 21. This arm makes a single turn around the screw 62 secured to the cheek plate 21 and then passes over to and under the projection 63 on the arm 51 and terminates beyond the projection 63 in the free arm element 64. The wire 58 is bent at 65 to form a seat for the projection 63 when the arm 51 is in neutral or open position of the switch. The portion 66 of the wire cooperates with the abutment 63 to lock the arm 51 in one closed position, and the arm portion 64 cooperates with the abutment 63 to anchor the arm 51 in its other closed position.

The wire 59 of the arm 52 is similar to the wire 58 except that it is not in alinement with the arm 58 but to a certain extent is the complement of the wire 58, the wire 59 having an arm portion 67 abutting against a screw similar to the screw 61 and then making a complete turn around another screw similar to the screw 62 and then extending down along the cheek plate 22 and engaging the abutments 68 in the arm 52, the abutment 68 being similar to the abutment 63 on the arm 51. The wire 59 also has a depression forming a seat cooperating with the abutment 68. It will be noted, however, that in the present instance, the arm 60 of the wire 58 extends adjacent to one end of the cheek plates 21 and 22 while the similar free arm of the wire 59, see Fig. 2, extends adjacent the other end of the switch. By this arrangement of the springs, the tension on the arms 51 and 52 to maintain them in either closed position will be substantially equal.

In order to actuate the two arms 51 and 52 by a common lever, the lever handle 69 is provided mounted on the blade 70 which is pivotally connected at one end to the arm 52 and slidably connected in a recess in the arm 51. When the handle 69 and blade 70 are positioned in the full line position shown in Fig. 3, the handle 69 is ready to actuate the arms 51 and 52 into either of its closed positions or into neutral position. When it is desired to ship the switch, however, in order to conserve space, the handle 69 is swung

down into the dash and dot line position shown in Fig. 3 adjacent the cheek plate 22.

In the present instance, the arm 51 is provided with an extension 71 having a finger 72 to rest in the recess 73 formed in the spring plate 74 which is secured by the spring 75 to the upper edge of the cheek plate 21. The spring plate 74 when its recess receives the pin 72 yieldably maintains the arms 51 and 52 in neutral position. The spring plate 74 has a projection 75 which, see Fig. 1, will be engaged by the cover 11 to depress the spring plate 74 and thereby free the finger 72 from the recess 73.

As will be hereinafter described, the cover 11 cooperates with the handle 69 to bring it into neutral position before the cover 11 can be removed. When it returns the arm or handle 69 into neutral position, then the finger 72 will register with the recess 73 and consequently immediately that the cover 11 is raised, the spring plate 74 will flex outwardly and receive the finger 72 and anchor the arms 51 and 52 and the handle 69 in neutral position. When it is desired to release the handle 69, it will be necessary to flex the spring plate 74 toward the cheek plate 21. This flexing can be achieved by merely closing the cover 11 into the position shown in Fig. 1.

The handle 69, see Fig. 1, has an enlargement 76 with a cam face 77 to cooperate with the edge 78 of the slot 79 in the cover 11. The rear edge 80 of the handle 69 will in turn cooperate with the edge 81 of the opening 79. In other words, when the cover 11 is in closed position, the handle 69 extends through the opening 79. The opening 79 is so conformed that the handle 69 can be moved into either of its circuit closing positions, when the cover 11 is closed, but when the cover 11 is swung around its hinge 10 into open position, if the handle 69 is in either of its closed positions, then either the edge 78 of the opening 79 will cooperate with the cam face 77 of the handle 69 or the edge 81 of the opening 79 will cooperate with the edge 80 of the handle 69 initially to return the handle 69 to its neutral position as shown in Fig. 1, when the finger 72 will register with the recess 73 ready to be anchored by the spring plate 74 immediately that the cover 11 clears the extension 75.

In operation the handle 69 from neutral position may actuate the arms 51 and 52 in turn to actuate the interposer 48 either to bring the contact 49 into engagement with the contact portions 34 and 30 and the contact 50 on the plate 48 into engagement with the contacts 37 and 25 or else swing the interposer 48 into the other circuit closing position where the contact will engage the contacts 35 and 31 and the contact 49 on the plate 48 will engage the contact plates 42 and 25. Looking at Figs. 5 and 6, assume that the binding posts 24 of the three switches 1, 2 and 3 are connected to the three conductors of a generator, then when the handle 69 is swung from neutral into closed position where the interposer 48 causes, see Fig. 5, the contact 49 to engage the plates 32 and 30 and causes the contact 50 to engage the contact plates 37 and 25, then the current will pass from a binding post 24 through the contact plate 25 to the contact 50, then the contact plate 37, then the clip 41 of the fuse, then the fuse 82 and then the fuse clip 40 and from the fuse clip 40 to the contact plate 32, the contact 49 on the interposer 48 and then the contact plate 30 to the binding post or terminal 83 of the power line connected to the contact

plate 30. In turn, see Fig. 6, where it is still assumed that the binding posts 24 are connected to the conductor of a generator and the interposer 48 is swung into the other closed position of the switch, the current will pass from the binding post 24 through the contact plate 25, then the contact 49 on the interposer 48, then the contact plate 36 to the clip 40 and through the fuse 62 to the clip 41, and from the clip 41 to the contact plate 37, then the contact plate 33 to the contact 50 on the interposer 48, then to the contact plate 29 to the binding post or terminal 84 of the second power line.

In Figs. 7 and 8, it is assumed that there are two generators or two generator systems connected to a single power line. In Fig. 7 it is assumed that the conductor 85 connected to one generator is connected to the binding post or terminal 84 and the conductor 86 of another generator is connected to the binding post or terminal 84 and the conductor 87 of the power line is connected to the terminal or binding post 24. If the handle 69 is moved into the closing position of the switch shown in Fig. 7, then the contact 49 of the interposer 48 will engage the contact plate 30 and the contact plate 32 and the contact 50 of the interposer will engage the contact plates 25 and 37. Consequently, the generator connected to the conductor 85 will be brought into connection with the power line 87 and the current will pass from the conductor 85 through the contact plate 30 to the contact plate 49 on the interposer 48, then the contact plate 32, then the contact plate 36 to the clip 40, from the clip 40 through the fuse 82, to the clip 41 and from the clip 41 to the contact plate 37 to the contact 50 in engagement with the contact plate 25 and from the contact plate 25 out to the binding post 24 to the power line 87.

In turn if the interposer 48 is swung into the position shown in Fig. 8, the generator connected to the conductor 86 will be thrown into connection with the power line 87 and the current will pass from the conductor 86 through the contact plate 29, to the contact 50, from the contact 50 to the contact plate 33 to the contact plate 37, to the clip 41, from the clip 41 through the fuse 82, from the fuse 82 through the clip 40 to the contact plate 36, from the contact plate 36 to the contact 49 and then to the contact plate 45 to the binding post 24 in turn to the power line 87.

The several fuses 82 are of conventional construction, each having at their ends knife blades 88 and 89, the blade 88 being adapted to be clamped by a clip 40 and the blade 89 to be clamped by a clip 41.

When the switch as illustrated consists of three switch elements, the several fuses 82 may be locked in position by the bar 90, it being in the present instance screw-threadedly connected to the upper edges of the cheek plates 21 and 22 by the screws 91 and 92 respectively. This bar in the present instance is preferably provided with a pin 93 so that the bar 90 with its pin 93 may serve a second function. In other words, when the bar 90 is in the position shown in Fig. 2, it will anchor the fuses 82 from being accidentally withdrawn. On the other hand, when it is desired to remove a fuse 82, the bar will first be removed and then its pin 93 may be used to be passed into the space 94, see Fig. 3, beneath the blade 88 or 89 of a fuse 82 and then the pin 93 be caused to press against the blade 88 or 89 and withdraw upwardly a fuse 82.

Furthermore, access is had to the fuse 62 located between the cheek plates 21 and 22 when the handle 69 is swung from the full line position shown in Fig. 3 to the dash and dot line position shown in that figure.

It is obvious of course that in place of the fuse 62 of each unit where it may be desired to dispense with a fuse, any suitable conductor such as a copper bar may be substituted, in which case of course the advantages of compactness afforded by the switch here disclosed will still be retained, and the incidental features that flow from such compact arrangement as herein before discussed will also be retained.

It is obvious that various changes may be made to the details of construction without departing from the general spirit of the invention as set forth in the appended claims.

I claim:

1. In an electric switch, the combination of a main terminal, a pair of secondary terminals, and means for alternately connecting said main terminal with either of said secondary terminals, said connecting means including a common fuse, a fuse contact plate connected to each end of said fuse, a main contact plate connected to said main terminal, a secondary contact plate connected to each of said secondary terminals, and an interposer slidably mounted between said main contact plate and the contact plates of said fuse and of said secondary terminals, said interposer having two contacts and three main positions, an intermediate neutral position where its two contacts are free, one closed position where one of its contacts bridges the gap between one fuse contact plate and the contact plate of one of said secondary terminals, and where the other of its contacts bridges the gap between the other fuse contact plate and the main contact plate, and the other closed position where said other of its contacts bridges the gap between the other of said fuse contact plates and the contact plate of the other of said secondary terminals, and where in turn the said first-mentioned of its contacts bridges the gap between said first-mentioned of its fuse contact plates and said main contact plate.

2. In an electric switch, the combination of a main terminal, a pair of secondary terminals, and means for alternately connecting said main terminal with either of said secondary terminals, said connecting means including a common fuse and an interposer having two contacts, said interposer being slidable into three positions, a neutral position where its two contacts are free, one closed position where one of its contacts bridges a gap between one end of said fuse and said main terminal, and the other contact bridges a gap between the other end of said fuse and one of said secondary terminals, and the other closed position where one of the contacts of said interposer closes a gap between one end of said fuse and said main terminal, and the other contact closes a gap between the other end of said fuse and the other of said secondary terminals.

3. In an electric switch, the combination of a main terminal, a pair of secondary terminals, and means for alternately connecting said main terminal with either of said secondary terminals, said connecting means including a common fuse, an interposer having two contacts, and separate contact plates connected to said main terminal, to said secondary terminals and to said fuse, being spaced from one another to form gaps, said interposer being slidable into three positions, a

5 neutral position where its two contacts are free, one closed position where its contacts close a gap between said main terminal and one end of said fuse and another gap between the other end of said fuse and one end of said secondary terminals, and another closed position where the contacts of said interposer close a gap between said main terminal and one end of said fuse and another gap between the other end of said fuse and said other secondary terminal.

4. In an electric switch, the combination of a plurality of switch units, each unit having a main terminal, a pair of secondary terminals, and means for alternately connecting the main terminal of each unit with either of the secondary terminals of each unit, said connecting means including a fuse for each unit, separate connecting plates connected to said main terminal, to said secondary terminals and to said fuse of each unit being spaced from one another to form gaps, a common slidably mounted interposer having a pair of contacts for each unit, said interposer being slideable into three main positions, a neutral position where its contacts are free, one closed position where the contacts of each unit close a gap between the main terminal and one end of the fuse and another gap between the other end of a fuse and one of the secondary terminals of each unit, and the other closed position where the contacts of each unit close a gap between the main terminal and one end of a fuse and another gap between the other end of a fuse and the other secondary terminal of each unit.

5. In an electric switch, the combination of a main terminal, a pair of secondary terminals, means for alternately connecting said main terminal with either of said secondary terminals, said connecting means including a common fuse and an interposer having two contacts, said interposer being slideable into three positions, a neutral position where its two contacts are free, one closed position where one of its contacts bridges a gap between one end of said fuse and said main terminal and the other contact bridges a gap between the other end of said fuse and one of said secondary terminals, and the other closed position where one of the contacts of said interposer closes a gap between one end of said fuse and said main terminal and the other contact closes a gap between the other end of said fuse and the other of said secondary terminals, a pivotally mounted arm, the free end of said arm being operatively connected to said interposer, and a handle operatively connected to the other end of said arm for actuating said arm and in turn said interposer.

6. In an electric switch, the combination of a main terminal, a pair of secondary terminals, means for alternately connecting said main terminal with either of said secondary terminals, said connecting means including a common fuse and an interposer having two contacts, said interposer being slideable into three positions, a neutral position where its two contacts are free, one closed position where one of its contacts bridges a gap between one end of said fuse and said main terminal and the other contact bridges a gap between the other end of said fuse and one of said secondary terminals, and the other closed position where one of the contacts of said interposer closes a gap between one end of said fuse and said main terminal and the other contact closes a gap between the other end of said fuse and the other of said secondary terminals, a pivotally mounted arm, the free end of said arm

being operatively connected to said interposer, a handle operatively connected to the other end of said arm for actuating said arm and in turn said interposer, and a spring for yieldably anchoring said arm in its neutral and closed positions.

7. In an electric switch, the combination of a main terminal, a pair of secondary terminals, means for alternately connecting said main terminal with either of said secondary terminals, said connecting means including a common fuse and an interposer having two contacts, said interposer being slidable into three positions, a neutral position where its two contacts are free, one closed position where one of its contacts bridges a gap between one end of said fuse and said main terminal and the other contact bridges a gap between the other end of said fuse and one of said secondary terminals, and the other closed position where one of the contacts of said interposer closes a gap between one end of said fuse and said main terminal and the other contact closes a gap between the other end of said fuse and the other of said secondary terminals, a pivotally mounted arm having its free end operatively connected to said interposer, a handle pivotally connected to the other end of said arm in one position to actuate said arm and in turn said interposer and the other position to be rocked out of the way to conserve space.

8. In an electric switch, the combination of a plurality of switch units, each switch unit having a main terminal, a pair of secondary terminals, means for alternately connecting the main terminal of each unit with either of the secondary terminals of each unit, said connecting means including a fuse for each unit, connecting plates connected to the main terminal, secondary terminals and fuse of each unit and forming gaps, a common slidably mounted interposer having a pair of contacts for each unit, said interposer being slidable into three main positions, a neutral position where its contacts are free, one closed position where the contacts of each unit close a gap between the main terminal and one end of the fuse and another gap between the other end of a fuse and one of the secondary terminals of each unit, and the other closed position where the contacts of each unit close a gap between the main terminal and one end of a fuse and another gap between the other end of a fuse and the other secondary terminal of each unit, pivotally mounted arms having their free ends operatively connected to said interposer, a handle operatively connected to the other end of said arm for actuating said arm, and spring means for anchoring said arm and in turn said interposer in its neutral and closed positions.

9. In an electric switch, the combination of a main terminal, a pair of secondary terminals, means for alternately connecting said main terminal with either of said secondary terminals, said connecting means including a common fuse and an interposer having two contacts, said interposer being slidable into three positions, a neutral position where its two contacts are free, one closed position where one of its contacts bridges a gap between one end of said fuse and said main terminal and the other contact bridges a gap between the other end of said fuse and one of said secondary terminals, and the other closed position where one of the contacts of said interposer closes a gap between one end of said fuse and said main terminal and the other contact closes a gap between the other end of said fuse

and the other of said secondary terminals, a housing for said switch having a pivotally mounted cover having a slot therein, a pivotally mounted arm having its free end operatively connected to said interposer, a handle operatively connected to said arm for actuating the same and extending through the slot in said cover when said cover is closed, said cover cooperating with said handle to position it in neutral position before said cover can be swung into open position.

10. In an electric switch, the combination of a main terminal, a pair of secondary terminals, means for alternately connecting said main terminal with either of said secondary terminals, said connecting means including a common fuse and an interposer having two contacts, said interposer being slidable into three positions, a neutral position where its two contacts are free, one closed position where one of its contacts bridges a gap between one end of said fuse and said main terminal and the other contact bridges a gap between the other end of said fuse and one of said secondary terminals, and the other closed position where one of the contacts of said interposer closes a gap between one end of said fuse and said main terminal and the other contact closes a gap between the other end of said fuse and the other of said secondary terminals, a housing for said switch, a pivotally mounted cover on said housing having a slot, a pivotally mounted arm having its free end operatively connected with said interposer to actuate the same, a handle operatively connected to said arm and extending through the slot in said cover, and a spring actuating means for anchoring said handle in neutral position when said cover is raised, said cover cooperating with said anchoring means to release said handle when said cover is in closed position to enable said handle to actuate said interposer.

11. In an electric switch, the combination of a base, three switch units mounted on said base, each switch unit having a main terminal, a pair of secondary terminals and means for each unit for alternately connecting its main terminal with either of its secondary terminals, the connecting means of each including a common fuse, and connecting plates forming gaps between the main terminal and said fuse and between the secondary terminals and said fuse, and a common interposer having a pair of contacts for each unit, said interposer being slidably mounted into three main positions, a neutral position where the contacts are free, one closed position where the contacts of each unit close a gap between its main terminal and one end of its fuse and close another gap between the other end of its fuse and one of its secondary terminals and another closed position where the contacts of each unit close a gap between its main terminal and one end of its fuse and close another gap between the other end of its fuse and the other of its secondary terminals, said connecting plates including clips for the ends of said fuses, said fuses having blade ends connected to said clips, said fuses being mounted parallel to one another, and an anchoring bar secured in place across the ends of said fuses to lock the same against accidental displacement.

12. In an electric switch, the combination of a base, three switch units mounted on said base, each switch unit having a main terminal, a pair of secondary terminals, and means for each unit for alternately connecting its main terminal with either of its secondary terminals, the connecting

means of each including a common fuse, connecting plates forming gaps between the main terminal and said fuse and between the secondary terminals and said fuse, a common interposer having a pair of contacts for each unit, said interposer being slidably mounted into three main positions, a neutral position where the contacts are free, one closed position where the contacts of each unit close a gap between the main terminal and one end of its fuse and close another gap between the other end of its fuse and one of its secondary terminals, and another closed position where the contacts of each unit close a gap between its main terminal and one end of its fuse and close another gap between the other end of its fuse and the other of its secondary terminals, said connecting plates including clips for the ends of said fuses, said fuses having blade ends connected to said clips, said fuses being mounted parallel to one another, an anchoring bar secured in place across the ends of said fuses to lock the same against accidental displacement, and a finger at the end of said anchoring bar for engaging the knife blades of said fuses when said bar is liberated to withdraw said fuses from said clips.

13. In an electric switch, the combination of a base, two parallel cheek plates mounted on said base forming three unit areas, an electric switch unit mounted in each unit area and including a main terminal, a pair of secondary terminals, means for alternately connecting each main terminal with either of its associated secondary terminals, the connecting means of each unit including a common fuse disposed in each unit area, connecting plates for each unit connected to the main terminal, secondary terminals and fuse of each unit to form gaps, a common interposer having a pair of contacts for each switch unit, the interposer being slidably mounted into three main positions, a neutral position where its contacts are free, one closed position where the contacts of each unit close a gap between a main terminal and one end of a fuse and the other end of a fuse with one of its secondary terminals, and the other closed position where the contacts of each unit close the gap between a main terminal and one end of a fuse and the other end of a fuse and the other of its secondary terminals.

14. In an electric switch, the combination of a base, two parallel cheek plates mounted on said base forming three unit areas, an electric switch unit mounted in each unit area and including a main terminal, a pair of secondary terminals, means for alternately connecting each main ter-

5 minal with either of its associated secondary terminals, the connecting means of each unit including a common fuse disposed in each unit area, separate connecting plates for each unit connected to the main terminal, to the secondary terminals and to the fuse of each unit spaced from one another to form gaps, a common interposer having a pair of contacts for each switch unit, the interposer being slidably mounted into 10 three main positions, a neutral position where its contacts are free, one closed position where the contacts of each unit close a gap between a main terminal and one end of a fuse and the other end of a fuse with one of its secondary terminals, and 15 the other closed position where the contacts of each unit close the gap between a main terminal and one end of a fuse and the other end of a fuse and the other of its secondary terminals.

15. In an electric switch, the combination of a base, two parallel cheek plates mounted on said base forming three unit areas, an electric switch unit mounted in each unit area and including a main terminal, a pair of secondary terminals, means for alternately connecting each main terminal with either of its associated secondary terminals, the connecting means of each unit including a conductor disposed in each unit area, 20 separate connecting plates for each unit connected to the main terminal, to the secondary terminals and to the conductor of each unit spaced from one another to form gaps, a common interposer having a pair of contacts for each switch unit, the interposer being slidably mounted into three main positions, a neutral position where its contacts are free, one closed position where the contacts of each unit close a gap between a main terminal and one end of its conductor and the other end of its conductor with one of its secondary terminals, and the other closed position 25 where the contacts of each unit close the gap between a main terminal and one end of its conductor and the other end of its conductor and the other of its secondary terminals.

STEPHEN S. GRADY.
